UNITED STATES PATENT OFFICE

138,305

DESIGN FOR A COAT

Angelo Del Re, New York, N. Y.

Application June 9, 1944, Serial No. 113,927

Term of patent 3½ years

(Cl. D3—4)

To all whom it may concern:

Be it known that I, Angelo Del Re, a citizen of the United States, residing in New York city, in the county of New York and State of New York, have invented a new, original, and ornamental Design for a Coat, of which the following is a specification, reference being had to the accompanying drawing, forming part thereof.

I claim:

The ornamental design for a coat, substantially as shown.

ANGELO DEL RE.
